COMBINED MICROPHONE AND TRANSMITTER

Burt E. Schell, Jr., Mundelein, Ill., assignor to Shure Brothers, Incorporated, Chicago, Ill., a corporation of Illinois

Application April 27, 1954, Serial No. 30,223

Term of patent 14 years

(Cl. D26—14)

To all whom it may concern:

Be it known that I, Burt E. Schell, Jr., a citizen of the United States, residing at Mundelein, in the county of Lake and State of Illinois, have invented a new, original, and ornamental Design for a Combined Microphone and Transmitter, of which the following is a specification, reference being had to the accompanying drawings forming a part thereof, in which:

Figure 1 is a perspective view of a combined microphone and transmitter embodying my new design;

Fig. 2 is a top plan view thereof, and

Fig. 3 is a front elevational view thereof.

I claim:

The ornamental design for a combined microphone and transmitter, substantially as shown.
